R. E. BARNARD

FLUME CONSTRUCTION

Filed March 1, 1927

UNITED STATES PATENT OFFICE.

RUSSELL E. BARNARD, OF DENVER, COLORADO, ASSIGNOR TO THE R. HARDESTY MANUFACTURING COMPANY, OF DENVER, COLORADO, A CORPORATION OF COLORADO.

FLUME CONSTRUCTION.

Application filed March 1, 1927. Serial No. 171,785.

My invention relates to improvements in sectional sheet metal flumes of the type shown and described in U. S. Patent No. 1,584,290, issued May 11, 1926, to Rudd 5 Hardesty.

In the flume construction disclosed in the patent, abutment sleeves and wedging shoes cooperate with suspension rods and bevel bars to secure the sections of which the flume 10 is composed in water-tight contact with each other and to suspend the structure from transversely disposed cross beams. It has been demonstrated in practical use that the shoes made separate from the sleeves are, 15 under certain conditions, disadvantageous particularly with respect to the assemblage of the parts when the flume is being constructed or repaired, and it is an object of the present invention to eliminate the shoes from the flume structure 20 by the provision of an abutment sleeve of novel construction which in addition to its own function, performs every function of the shoe with equal if not better effect and 25 which greatly facilitates the work of assembling the parts of the flume structure in their proper relative positions.

An embodiment of the invention has been 30 illustrated in the accompanying drawings in which like parts are similarly designated throughout the several views and in which

Figure 1 represents a fragmentary side elevation of a flume constructed in accordance 35 with my invention,

Figure 2, a transverse section along the line 2—2 Figure 1, drawn to an enlarged scale,

Figure 3, a further enlarged section of one 40 of the improved distance sleeves together with the other parts of the flume suspending means, with which it is directly associated,

Figure 4, a section taken on the line 4—4, Figure 3,

Figures 5 and 6, views similar to Figure 45 3, showing modifications in the construction of the abutment sleeve, and

Figure 7, an enlarged section along the line 7—7, Figure 2.

The flume structure as shown in the drawings 50 comprises a series of longitudinally aligned semi-cylindrical sheet metal sections 5 which overlap one another at their adjoining ends. The lapping ends of the sections are beaded as indicated at 6 in Figure

7, and they are engaged at opposite sides 55 by a suspension rod 7 and a so-called bevel bar 8 both curved in conformity with the flume.

The rod 7 which is disposed exteriorly of the flume, has its ends projecting through 60 vertical bores in one of a number of cross beams 9 from which the flume is suspended, the bores being bushed with the metal abutment sleeves 10 which are the principal subject of the present invention. 65

The sleeves as shown in Figures 2 and 3, each consist of a tubular body portion 10^a having at the lower end thereof an integral lateral projection 10^c the under surface 10^d of which is beveled to bear upon the corresponding end of the respective bevel bar with a wedging effect. 70

The upper ends of the rods are screw-threaded for the application of nuts 12 which in practice bear upon washers 13 75 placed in engagement with the upper ends of the sleeves. When the nuts are screwed down upon the washers the rod is drawn tightly around the lapping ends of the flume sections while at the same time the bevel bar is forced inwardly by the wedging action of the beveled projections at the lower ends of the sleeves. 80

The rods indent the beads of the flume sections as illustrated in Figure 7 and the 85 several parts of the suspension element, thus cooperate to produce a water-tight joint between the sections.

The abutment sleeve illustrated in Figure 3 may be made of wrought or cast iron, 90 while that shown in Figure 5 can be made of flat material die-cut and formed with an open side seam, or of tubing cut to provide the slanting lip 10^e which as in the first described form of the invention, is the part by 95 which the bevel is forced to engagement with the inner surface of the flume.

In the form shown in Figure 6, the sleeve has in addition to the projection 10^c and in opposed relation to the same, a downwardly 100 projecting tongue 10^f which by engagement with the suspension rod prevents the rod from being canted when the nuts are screwed home upon the washers.

The sleeves made as shown and hereinabove described provide a dependable, strong and rigid means for the suspension of the flume and the water-tight connection of the 105

sections of which it is composed, they permit of self-adjustment of the flume structure in case of shrinkage or decomposition of the wooden cross beams without re-adjustment of the nuts and they furthermore provide a space between the flume and the cross beams that permits of the passage of rubbish and thereby prevents clogging of the flume.

The omission of separate wedging shoes evades displacement and breakage and greatly facilitates the construction of the flume and the entire structure is more rigid and stronger with the added advantage of being composed of a less number of parts.

Having thus described my invention, what I claim and desire to secure by Letters Patent is:—

1. As a new article of manufacture, an abutment sleeve for flume structures comprising a tubular body member, and at an end thereof, an integral lateral projection having a wedging surface slanting relative to the axis of the body member.

2. As a new article of manufacture, an abutment sleeve for flume structures comprising a tubular body member and at an end thereof, an integral lateral projection having a wedging surface slanting relative to the axis of the body member, and opposite to said projection, an integral downwardly ranging tongue.

3. In a flume structure, the combination with a flume and a cross beam having openings for the suspension thereof, of a rod and a bevel bar engaging the flume at opposite sides thereof, the rod projecting through the openings of the beam, bushings in the open-

ings, having integral projections bearing on the ends of the bevel bar, and nuts on the ends of the rods, bearing on the bushings. 40

4. In a flume structure, the combination with a flume and a cross beam having openings for the suspension thereof, of a rod and a bevel bar engaging the flume at opposite sides thereof, the rod projecting through the 45 openings of the beam, bushings in the openings, having integral projections bearing on the ends of the bevel bar, and nuts on the ends of the rods, washers engaging the upper ends of the bushings, and nuts bearing on the 50 washers.

5. In a flume structure, the combination with a flume and a cross beam having openings for the suspension thereof, of a rod and a bevel bar engaging the flume at opposite 55 sides thereof, the rod projecting through the openings of the beam, bushings in the openings, having integral projections bearing on the ends of the bevel bar, and having opposite to said projections, integral downwardly 60 ranging tongues bearing on the rod, and nuts on the ends of the rod, bearing on the bushings.

6. In a flume structure, the combination with a flume and a cross beam having openings for the suspension thereof, of a rod and a bar engaging the flume at opposite sides thereof, the rod projecting through the openings in the beam, bushings in the openings 70 engaging on the ends of the bar, and nuts on the ends of the rods bearing on the bushings.

In testimony whereof I have affixed my signature.

RUSSELL E. BARNARD.
